DESCRIPTION

FIG. 1 is a perspective of a molded surface of a concrete product according to our new design;

FIG. 2 is a front elevational view thereof;

FIG. 3 is a right side elevational view thereof;

FIG. 4 is a left side elevational view thereof;

FIG. 5 is a top view thereof; and,

FIG. 6 is a bottom view thereof.

The broken lines in all views are included for the purpose of illustrating portions of the concrete product that form no part of the claimed design.
